JAMES N. MOULTON, OF HAVERHILL, MASSACHUSETTS.

FORMING-IN MACHINE.

1,089,491.

Specification of Letters Patent. Patented Mar. 10, 1914.

Application filed June 3, 1912. Serial No. 701,184.

To all whom it may concern:

Be it known that I, JAMES N. MOULTON, a citizen of the United States, and resident of Haverhill, in the county of Essex and State of Massachusetts, have invented certain new and useful Improvements in Forming-In Machines, of which the following is a specification.

This invention has relation to machines for preparing inner soles of the type in which the inner face of the inner sole is covered with a layer of adhesive fabric.

The particular object of the present invention is to provide a machine for forming-in the fabric, that is, forcing the fabric into the angle formed by the upper inner surface of the sole body and the inside wall of the lip, and causing it to adhere thereto, so that, in the subsequent operation of attaching the welt and the upper to the inner sole, there will be a sharp reentrant angle formed by the fabric into which the needle of the welt sewing machine may penetrate.

On the accompanying drawings,—Figure 1 illustrates in side elevation the machine which embodies the invention. Fig. 2 represents a plan view of the same. Fig. 3 represents a section on line 3—3 of Fig. 1 and illustrates the forming-in tool as operated upon the work. Fig. 4 represents a section through the forming-in tool and its carrier. Fig. 5 represents an enlarged section on the line 5—5 of Fig. 3. Fig. 6 shows in plan view the feeding wheel which bears upon the marginal portion of the sole and against the upturned lip. Fig. 7 shows a detail of the clutch and its actuating mechanism.

On the drawings,—the frame of the machine is indicated at 10 and may be of suitable construction, being provided as indicated with an upright arm 11 and with an upstanding tubular flange 12 which constitutes a bearing for the rotatable and vertically movable spindle 13. Secured upon the upper end of the spindle 13, which projects above the bearing 12, there is a substantially flat rotatable disk 14 which constitutes a support for the work. This disk is beveled at its edge as indicated. Overlapping the beveled portion of the work support 14 is a knurled feed wheel 15, see Figs. 1 and 6, the under face of which is beveled as indicated to engage the feather or marginal portion of the inner sole, as illustrated in Fig. 5. The periphery of this feed wheel is cylindrical and it is approximately equal

in length to the height of the upstanding lip of the inner sole so as to support the lip from its edge to its connection with the body of the inner sole at the point where the forming-in tool is operating.

16 indicates the forming-in tool which has a substantially flat end adapted to bear upon that portion of the fabric which lies upon the face of the inner sole, to press the fabric firmly downward, and which is also formed with a side wall or face substantially equal in height to the lip of the inner sole, so as to press the fabric against the upstanding lip, as illustrated in Fig. 5. The side wall 70 and the end or bottom of the tool are at such an angle that they force the fabric well into the angle formed by the lip and the body of the inner sole. The tool is held downward yieldingly by spring pressure, 75 which increases as the tool is swung about a pivot toward and from the feed wheel to smooth the fabric toward the lip and force it firmly thereagainst to cause it to adhere thereto, after which, when the tool is moved 80 away from the feed wheel, the downward pressure of the spring is decreased so as to permit the feeding of the work underneath the tool.

The spindle 13 for the work-supporting wheel or disk 14 is reduced in diameter as illustrated in Fig. 1, and its lower threaded end is connected by a coupling 17 with a rod 18 which may be moved downwardly by a treadle, not shown, so as to depress the spindle against the tension of a supporting spring 19 which is located between a shoulder on the spindle and the shoulder formed on the frame. Nuts 20, screwed on a threaded portion of the spindle, may be rotated to 90 adjust the work-supporting wheel vertically with reference to the feed wheel 15 and the tool 16.

The feed wheel 15 is secured in any suitable way upon a shaft 21 parallel to the spindle 13, the means shown comprising a collar 22 and a countersunk binding screw 23. The shaft 21 is journaled in a bearing 24 projecting laterally from the tubular flange or bearing 12, the lower end of the shaft 21 being stepped in the bearing in the bottom portion of the frame. Gears 25 26 operate to transmit power from the shaft 21 to the spindle 13, one of these 110 gears being wide enough to preserve their intermeshed relation when the spindle 13

and work support are depressed for the insertion of the work between the work support, the feed wheel and the tool.

Power is transmitted to the shaft 21 from

- 5 a prime power shaft 27 by the following mechanism: On the shaft 27 is a belt pulley 28 from which power is transmitted by a belt 29 to a small pulley 30 on a cross shaft 31 journaled in the lower portion of 10 the frame. The last-mentioned shaft 31 is equipped with a worm 32 intermeshing with and driving a worm wheel 33 on the shaft 21. In the mechanism thus described, it will be apparent that the feed wheel and the 15 work-supporting wheel will be rotated about their axes in opposite directions, although their overlapping portions will move in the same direction.

For transmitting power to the prime

- 20 power shaft, I may utilize any convenient clutch-controlled mechanism, although I find the mechanism which I shall now describe to be eminently satisfactory for the purpose.

- 25 34 is a slidable belt pulley loose upon the shaft and having an internally beveled rim which constitutes one clutch member adapted to coöperate with a clutch member 35 fast upon the shaft 27. The grooved hub of the belt pulley 34 is engaged by inwardly projecting members 36 on a forked shelling lever 37 pivoted upon a pin 38.

- 39 is a shaft arranged horizontally and extending from the rear portion of the machine toward the front thereof and it is provided with a hand wheel 40 by which it may be rotated. On its rear end the shaft 39 has a crank pin 41 which is connected with the lever 37 by a connecting rod 42 pivoted to the latter by a screw pin 43. By 40 rotating the shaft 39 through an arc of 180°, the clutch pulley will be thrown into clutched engagement with, or will be disengaged from, the clutch 35, and, by reason of 45 the crank and link connection between the lever 37 and shaft 39, it may be locked in either position to which it is moved.

- The forming-in tool 16 is formed with a shank 44 secured in a socket in the lower end 50 of a plunger 45. The plunger 45 is mounted in an oscillatory head 46 which is socketed, as shown, to receive a spring 47, the lower end of which engages a flange 48 on the plunger, and the upper end of which engages 55 an adjustable cap screw 49 threaded into the upper end of the head and locked in place by a lock nut 50. The reduced upper end of the plunger projects loosely through the cap screw 49 and is provided with adjusting and lock screws 51 52. The plunger 60 is held against rotation by a pin 53 which projects into a vertical groove therein. The head 46 is secured upon the end of a lever 54 which is fulcrumed upon a pivot pin 55 65 secured in the end of the upstanding arm

11. The rearwardly extending arm of the lever 54 is connected by a connecting rod with an eccentric strap 56 which encircles an eccentric 57 secured to a shaft 58 arranged in parallelism with the shaft 27. A gear wheel 59 on the shaft 27, engaging a pinion 60 on the shaft 58, transmits power to the latter. The connecting rod, last referred to, is formed in adjustable sections so that it may be extended or contracted 70 for the purpose of adjusting the tool 16 and head 46 toward and from the work-supporting wheel 14 and the feeding wheel 15.

The feed wheel and the forming-in tool both operate to hold the work upon the work-supporting wheel, although the pressure of the forming-in tool upon the work decreases as the head 46 is swung about the axis of the pivot 53 away from the feed wheel. If desired, the nuts 51 52 may be 85 adjusted to raise the forming-in tool slightly so that it may be entirely disengaged from the inner sole when it reaches the extreme of its upward movement. The parts are all actuated so as to move rapidly, the power-transmitting gearing being constructed as described with this purpose in view.

Having thus explained the nature of my said invention, and described a way of making and using the same, although without 95 attempting to set forth all of the forms in which it may be made or all of the modes of its use, what I claim is:

1. In a machine for preparing insoles, a de- 100 pressible rotatable horizontal work support, a member arranged to tuck reinforcing material into the angle behind the lip of the insole, and having a curved face at its end and a side face at an angle to its end face, and means for causing said tucking member 105 to bear upon the reinforcing material on the flat part of the sole behind the lip, and to move thereon toward and from the lip, said means being adapted to increase the pressure of said tucking member upon the work 110 when it moves toward the lip, and to decrease the pressure when said member moves away from the lip, and a fixed feed wheel having its axis parallel to the work support, 115 said feed wheel bearing upon the feather of the sole and engaging the lip to hold it upright against the pressure of the tucking member.

2. In a machine for preparing insoles, a de- 120 pressible yielding rotatable work support, a member arranged to tuck reinforcing material into the angle behind the lip, a fixed rotatable feeding member adapted to engage the outer side of the lip and the upper face of the feather, means for driving said work-support and feeding member continuously, and pressure means for causing said tucking member to bear upon the reinforcing material on the flat part of the sole behind the lip, said pressure means being adapted 125 130

to alternately increase and decrease the pressure of said tucking member upon the work and move said member toward and from the lip.

5 3. In a forming-in machine, a depressible rotatable work-supporting wheel arranged substantially horizontally to provide a flat surface for the work, a fixed rotatable feed wheel overlapping the edge of the work-supporting wheel and adapted to clamp the feather of the inner sole against said work-supporting wheel, the periphery of the feed wheel being elongated to engage and support the lip to its edge, an oscillatory forming-in tool having an under end face to press against reinforcing material on the surface of the sole and a side face to press against the lip so as to force the reinforcing material into the angle formed by the 10 lip and the body of the insole, and yielding means for oscillating said forming-in tool.

15 4. In a forming-in machine, a horizontal work-supporting wheel having a flat face for the reception of the work, an overlap-

ping feed wheel adapted to clamp the feather of the work against the marginal portion of the feed wheel and to support the lip in raised position, parallel vertical shafts respectively secured to said wheels, gears connecting said shafts, means for 20 yieldingly supporting the shaft for said work-supporting wheel, adapted to permit it to be depressed for the insertion of the work, an oscillatory lever having a head on one end, a forming-in tool yieldingly mounted in said head above said work-supporting wheel and angularly formed to force the fabric into the angle formed by the lip and the body of the sole, and instrumentalities for positively actuating 25 said shafts and oscillating said lever.

In testimony whereof I have affixed my signature, in presence of two witnesses.

JAMES N. MOULTON.
